DRAWER MECHANISM FOR CASH REGISTERS

Arthur C. Kirshner, Dayton, Ohio, assignor to The National Cash Register Company, Dayton, Ohio, a corporation of Maryland

Application May 20, 1937, Serial No. 143,635

9 Claims. (Cl. 45—7)

This invention pertains to a drawer mechanism for cash registers and other drawer equipped devices.

The general object of the invention is to provide means for arresting the drawer action at a predetermined point between the closed and fully opened positions with further means for enabling the operator to thereafter release the arresting mechanism, if desired, and open the drawer to its full extent.

The particular embodiment here set forth shows the invention applied to a cash register drawer. The usefulness of the invention for this purpose is in arresting the expelled cash register drawer at a point where the front part of the till will be exposed while the rear part remains in the drawer frame. In ordinary retail trade many transactions need only fractional currency for change making, which, being ordinarily in the front part of the drawer, is always exposed by such arrested opening of the drawer while the larger denominations of currency remain protected against pilfering. If the operator wishes to get into the rear of the drawer, the arresting mechanism may be released by a slight inward motion of the drawer and then the drawer can be completely extended. A further advantage of the invention as applied to cash registers is its use in stores having narrow aisles behind the counters, where often a fully loaded and extended drawer would block the movements of or strike clerks other than the operator.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In the drawing:

Fig. 1 is a top view of the right side of a cash register drawer and adjacent frame, both partly broken away to show the mounting of the parts.

Fig. 2 is a side elevation of the drawer in its closed position with the side of the frame removed, with the drawer release mechanism shown.

Fig. 3 is an enlarged view of the bracket 16 and roller 17 as shown in Fig. 2.

Fig. 4 is a side elevation of the drawer in the arrested open position with the side of the drawer frame removed.

Fig. 5 is a side elevation of the drawer in the fully extended position with the side of the drawer frame removed.

Fig. 6 is a view of the space between the right side of the drawer and the frame looking from front to rear, at line 6—6 in Fig. 4, showing the alignment of the parts.

The drawer 10 (Fig. 1) has, fastened to either side and running its full depth, angle bars, the right one of which is shown at 11 (Figs. 1, 2, 4 and 5), which act as bearing surfaces for the forward and backward movement of the drawer on flanged rollers 12 (Figs. 1, 2, 4 and 5). Rollers 13 (Figs. 1, 2, 4 and 5) resting on the upper side of the bearing surface of the angle bars 11 oppose any vertical play of the drawer by confining the movement of said angle bars. Rollers 13 also serve to keep the back end of the drawer from rising against the top of the frame due to the tendency of the front of the open drawer to drop after the angle bars have moved forward with the drawer and the major part of the weight of the drawer has passed forward of the front rollers 12 sufficiently to leave the rear rollers 13 (Fig. 5). Rollers 12 and 13 are attached by studs 14 (Fig. 2) to the sides of the drawer frame 15 (Fig. 1). The periphery of the rollers 12 extending beyond the flanges serve to steady the drawer against lateral movement. This results in a free moving drawer with a minimum of vertical or lateral play.

The drawer 10 has fastened on its right side near the rear end an inverted U-shaped bracket 16 (all figures) whose purpose is to support a roller tappet 17 (all figures) whose axis is perpendicular to the side of the drawer. The axis of the roller tappet is carried at either end in vertical slots 18 (Fig. 3) in the bracket 16 in such a manner that the roller tappet is free to move up and down and rotate at the same time. The roller tappet 17 is normally resting at the bottom of the slots 18 and is yieldingly retained there under the influence of springs 19 (Figs. 3 and 6) fastened between each end of the axis of the roller and the bottom of bracket 16. The springs 19 are looped at their upper ends to fit circumferential grooves cut into the ends of the axis of the roller. The rotation of the roller tappet 17 is for anti-frictional purposes. The vertical movement of the roller tappet serves, in conjunction with a slide or detent 26 (Figs. 1 and 2) and a by-pass bell crank pawl 27 (Figs. 1, 2, and 6), to arrest the drawer, as it opens, at a point short of the maximum extension of the drawer and upon further manipulation to release the drawer from the arresting mechanism. This operation will now be described.

The detent 26 is mounted on two studs 28 pro-

truding on the inside of the drawer frame in such a manner that it may be moved forward or backward a short distance. The forward end of the detent has a nose 30 (Fig. 2), the purpose of which will be later explained. The upper edge of the detent has a hump 29 so positioned that when the drawer starts forward the roller tappet 17 will strike it on the rear slope, knocking it forward on its studs from the position shown 10 in Fig. 2 to that shown in Fig. 4. The roller tappet 17, by meeting the slope of the hump, is thrust upward in slots 18, and, the drawer continuing its forward motion, the roller tappet is carried over the hump. The forward motion 15 of the detent 26 carries the previously mentioned nose 30 over the rearwardly extending arm of the bell crank by-pass pawl 27 (Figs. 4), which is mounted on a stud projecting inwardly from the right side of the drawer frame. This stud 20 acts as an axis of rotation for the pawl in a plane coinciding with the plane of movement of the detent 26 and the forward moving roller tappet 17. The normal position of the bell crank pawl 27 is shown in Fig. 2 as it is retained 25 in that position by a spring 31 (Fig. 6) which gives sufficiently to allow the roller tappet 17 to pass forward, as shown in Fig. 5, when the slide is in the rearward position shown in Fig. 2. Continuing the progress of the opening drawer which 30 is forcibly expelled from the closed position by spring 32 (Figs. 2 and 3), and which has been followed until the roller tappet 17 has jumped the hump 29 (Fig. 2), the downward pull of springs 19 on the roller 17 is not sufficient to 35 hold it to the forward slope of hump 29, as the forward movement of the drawer is fast enough to prevent that from happening. Consequently, jumping from the crest of the hump, the roller tappet 17 contacts the upper arm of the pawl 27 as shown in Figs. 4 and 6. The pawl, being 40 unable to turn counter-clockwise, due to the nose 30 of slide 26 blocking the movement, stops the roller tappet and therefore the drawer (Fig. 4). The point at which the drawer is arrested 45 is determined by the placing of the slide 26 and the pawl 27, therefore the drawer may be built with any interior arrangement and the arresting mechanism positioned accordingly.

If, after having opened to the arrested position, it is desired to have the drawer extended 50 to its full length, the drawer is manually pushed inwardly, gently, a short distance so that the roller tappet 17, now resting on the nose of the slide due to the action of springs 19, strikes the forward slope of the hump 29 and pushes the slide to its rearward position. This withdraws 55 the nose 30 from the pawl 27, leaving it free to rotate on its axis under control of its spring. Now the drawer can be pulled forward, as the roller, striking the upwardly extending arm of 60 the pawl, rotates the pawl in a counter-clockwise direction, thereby permitting the roller tappet to pass by and the drawer to open to its full extent. The pawl returns to its normal position before mentioned by the action of its 65 spring 31.

The operation of closing the drawer results 70 in the roller tappet 17 striking the front side of the upwardly extending pawl arm and rotating the pawl in a clockwise direction until the roller tappet 17 can pass, as shown in Fig. 5, whereupon the pawl returns to normal. The continued rearward movement of the drawer causes 75 the roller to strike and rise over the hump 29. The operator normally closes the drawer with

sufficient force to carry the roller over the hump without the rear slope being contacted. Failure so to clear the hump and the resulting forward motion given to the detent only anticipates the first action of the roller on the next outward movement of the drawer, so the drawer may be closed at any speed. The spring 32 engages the cupped back-stop 33 (Fig. 2) and the prong 34 (Fig. 2) carried by the drawer is engaged with a latching mechanism shown in Fig. 2. The prong 34 is released upon the pressing down of a key 35 through a well known mechanism for the press-down key cash register described in United States Patent No. 790,104, issued to Thomas Carney on May 16, 1905. 15

As the manner of drawer release is not material to this invention, the mechanism shown is not described, but reference is made to Patent No. 790,104, issued to Thomas Carney on May 16, 1905, for such description if desired. It 20 is obvious that any well known form of drawer release mechanism may be used.

While the invention herein described has been shown as applied to one side of the drawer, it is obvious that it may be duplicated on the opposite side if desired. 25

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow. 30

What is claimed is: 35

1. In a cash register, the combination of a drawer slidably mounted in a frame; a drawer latch; means for releasing the latch; a spring mounted on the rear of the drawer to force it outward; a roller tappet capable of vertical movement mounted on the side of the drawer; a detent movably mounted on the wall of the drawer frame adapted to be moved forward as the roller tappet passes over it when the drawer moves to open position and to be moved rearward as the roller tappet strikes or passes over it when the drawer moves to closed position; and a by-pass pawl rotatably mounted on the drawer frame, designed to engage the roller tappet when the detent is in the forward position and to allow the tappet to pass in either direction when the detent is in the rearward position. 40

2. In a cash register, the combination of a drawer slidably mounted in a frame; a drawer latch; means for releasing the latch; means for forcibly ejecting the drawer from closed to open position; a roller tappet capable of vertical movement mounted on the side of the drawer; a detent movably mounted on the wall of the drawer frame adapted to be moved forward as the roller tappet passes over it when the drawer moves to open position and to be moved rearward as the roller tappet strikes or passes over it when the drawer moves to closed position; and a by-pass pawl rotatably mounted on the drawer frame and designed to engage the roller tappet when the detent is in the forward position and to allow the tappet to pass in either direction when the detent is in the rearward position. 45

3. In a cash register, the combination of a drawer slidably mounted in a frame; means for forcibly ejecting the drawer from closed to open position; a latch holding the drawer in closed position; means for releasing the latch and rendering the ejecting means operative; a tappet 50

movably mounted on the drawer; a detent movably mounted on the drawer frame, moved in one direction by the tappet as the drawer opens from closed position and moved in the reverse direction by the tappet as the drawer closes; and a by-pass pawl movably mounted on the drawer frame designed to be locked by movement of the detent on forward movement of the drawer causing the drawer to be arrested in partly opened position and to be unlocked by movement of the detent on rearward movement of the drawer.

4. In combination, a drawer, a frame in which the drawer is slidably mounted; a drawer stop actuated by forward movement of the drawer; a bolt engaging the stop and arresting forward movement but permitting rearward movement of the drawer; and drawer operated means for releasing the bolt from the stop allowing further forward movement of the drawer from arrested position and unrestricted rearward movement to closed position.

5. In combination, a drawer; drawer actuated means for stopping the forward movement of the drawer at a point short of full extension; and drawer actuated means for releasing said stopping means allowing the drawer to travel to full extended position or to return to closed position.

6. In a cash register, in combination, a drawer; drawer actuated means for stopping the forward movement of the drawer at a point short of full extension; and drawer actuated means for releasing said stopping means allowing the drawer to travel to full extended position or to return to closed position, said return of the drawer to closed position restoring the stopping means to effective condition.

7. In a cash register, the combination of a drawer slidably mounted in a frame; a means to eject the drawer to open position; a roller tappet capable of vertical movement mounted on the side of the drawer; a detent movably mounted on the wall of the door frame adapted to be moved forward as the roller tappet passes over it when

the drawer moves to open position and to be moved rearward when the roller tappet strikes or passes over it when the drawer moves to closed position; and a by-pass pawl rotatably mounted on the drawer frame designed to engage the roller tappet when the detent is in the forward position and to allow the tappet to move to forward position when the detent is in the rearward position.

8. In a cash register, the combination of a drawer slidably mounted in a frame; a tappet movably mounted on the drawer; a detent movably mounted on the drawer frame, moved in one direction by the tappet as the drawer opens from closed position and moved in the reverse direction by the tappet as the drawer closes; a by-pass pawl movably mounted on the drawer frame designed to be locked by the movement of the detent on forward movement of the drawer causing the drawer to be arrested in partly opened position and to be unlocked by movement of the detent on rearward movement of the drawer.

9. In a cash register having a main operating means operated at each operation of the cash register; a cash drawer slidably mounted in the cash register; means for impelling said cash drawer toward complete outward position; and a restraining means normally keeping said cash drawer in its innermost position but operable on operation of the main operating means to release the drawer from its innermost position and permit its movement outwardly under the action of its impelling means, the combination of a second restraining means for said cash drawer being normally ineffective and rendered effective by the movement of the drawer toward outward position to restrain said drawer in an intermediate position on its outward movement; and means whereby said second restraining means is rendered ineffective by a slight inward movement of the drawer thus to permit the movement of the drawer toward its complete outward position.

ARTHUR C. KIRSHNER.
